UNITED STATES PATENT OFFICE

140,298

DESIGN FOR A SOFA BED HINGE

William W. Wilson, Memphis, Tenn.

Application October 5, 1944, Serial No. 115,624

Term of patent 14 years

(Cl. D10—9)

To all whom it may concern:

Be it known that I, William W. Wilson, a citizen of the United States of America, residing at Memphis, in the county of Shelby and State of Tennessee, have invented a new, original, and ornamental Design for Sofa Bed Hinges, of which the following is a specification, reference being had to the accompanying drawings, forming part thereof.

In the drawings:

Fig. 1 is a side elevational view of a sofa bed hinge showing my new design.

Fig. 2 is an edge view of the hinge looking in the direction of the arrow II of Fig. 1.

Fig. 3 is an elevational view of the opposite side of the hinge; and

Fig. 4 is an edge view of the article looking in the direction of the arrow IV of Fig. 3.

I claim:

The ornamental design for a sofa bed hinge, substantially as shown.

WILLIAM W. WILSON.
